RADIO RECEIVING CIRCUIT ARRANGEMENT

Frederic Calland Williams, Great Malvern, England, assignor to Minister of Supply in His Majesty's Government of the United Kingdom of Great Britain and Northern Ireland, London, England

Application August 21, 1946, Serial No. 692,084
In Great Britain March 13, 1943

Section 1, Public Law 690, August 8, 1946
Patent expires March 13, 1963

3 Claims. (Cl. 250—20)

1

This invention relates to radio receiving circuit arrangements operating on the regenerative principle, and, although applicable generally to such receivers, is of particular application to super-regenerative receivers. In particular, the efficient operation of the super-regenerative receivers described in the specification of my co-pending U. S. Patent application Serial No. 692,085, filed August 21, 1946, now Patent No. 2,592,777 granted April 15, 1952 has been found to be improved by the application of the present invention.

Super-regenerative receivers are notoriously critical in the adjustment of their circuit parameters to give reliable and sensitive reception. The sensitivity normally varies from time to time with change of frequency, aerial loading, supply voltages and with component variations from one receiver to another.

The circuit arrangement described in the specification referred to, comprises a super-regenerative receiver which is operating under very arduous conditions and operation of the circuit with the desired degree of stability is difficult. In the particular circuit arrangement described, the grid of a super-regenerative valve has fed to it, in addition to the quench voltage, an inhibiting voltage which renders the valve inoperative when desired, and the tuned circuit, which is variable over a wide range, is common to a transmitting valve which has pulse feed-back connection to its control grid. Difficulties of maintaining stability in this circuit are thus increased due to the complexity of the circuits coupled to the control grid of the super-regenerative valve.

As is well known arrangements have previously been proposed for effecting automatic control of the overall amplification or gain of both super-heterodyne and super-regenerative type receivers whereby a substantially constant value of output signal is obtained with widely varying values of signal input. Such arrangements involve wide variation of the receiver sensitivity, in the presence of and under the control of the input signal. The present invention is distinguished from such arrangements by having as its object, not the maintenance of a constant value of output signal but on the contrary, the maintenance of a constant value of sensitivity in a regenerative receiver in the absence of any input signals. In this way the operation of a regenerative receiver may be rendered more reliable.

In the absence of any signal input to a receiver an output is obtained from the detector in the form of a "noise" or "hiss" voltage. In the case of a super-regenerative receiver, this "noise" is

primarily due to radio frequency oscillations in the receiver on each quench cycle building up from the random noise in the receiver tuned circuits and, therefore, has a very strong component at quench frequency although the receiver output also contains components spread out in frequency over the whole of the pass band of the receiver.

According to the present invention, in a circuit arrangement including a valve arranged to operate regeneratively the gain is stabilised in the absence of an input signal, by means of a direct current voltage which is obtained by rectification of current representing "noise" in the circuit, the direct current voltage being fed to the valve in such a manner that any tendency towards alteration of the general level "noise" oscillations in the output circuit of the valve is resisted, or eliminated.

In a particular circuit arrangement embodying the invention, the valve is operated super-regeneratively and the direct current voltage is derived from a circuit tuned to the quenching frequency employed, the rectified voltage being fed as a biasing potential to the control grid of said valve. The tuned circuit employed may be constituted by a coupling transformer the output from which is rectified before application to the super-regenerative valve.

In order that the invention may be more clearly understood, and readily carried into effect, alternative circuit arrangements designed to operate in accordance therewith will now be more fully described by way of example, with reference to the accompanying drawings in which:

Figure 1 shows a responder circuit suitable for indicating identification of, for example, an aircraft under interrogation, as described in the specification of my co-pending U. S. Patent application S. No. 692,085, filed August 21, 1946, and Figure 2 shows a modification.

Referring to Figure 1 of the drawings, an incoming interrogating signal in the form of a number of separate radio frequency pulses is fed from an aerial socket, P8, through a coupling coil, L7 to the main oscillatory circuit, L6, C9, the tuning of which is repeatedly swept once every three seconds through a frequency band of 30 megacycles per second between 157 and 187 megacycles per second.

The received signal is fed to a super-regenerative valve, V2, to which quenching oscillations are also fed from a quenching valve, V1. The signal output from valve V2 triggers an oscillator valve V3 which is normally biased to cut off. This triggering action is effected by feeding the re-

ceived signal oscillations occurring in the circuit L₆, C₉ to a diode V₄ where they are rectified and the rectified signal then applied to the grid of an amplifier V₅, which is coupled in turn to a valve V₆ having a cathode load resistance R₁₆. The output voltages, in the form of positive-going voltage pulses appearing at the cathode end of the resistance R₁₆ are fed back to the control-grid of the oscillator valve V₃ where they act to reduce the negative bias potential and so permit the valve to burst into oscillation. As the resonant circuit L₆, C₉ will still be tuned to the frequency of the received signal which initiated the triggering action, the final result is the generation and radiation through coupling coil L₇ and the aerial socket P₃ of a counter part or response signal pulse for each of the received signals appearing at the output valve V₆. The high-frequency oscillations persist for a period of time which is determined principally by the constants of the coupling circuit between the valve V₅ and V₆, and more particularly by the values of the condensers C₂₀, C₁₉, the latter of which is controlled by a signal coding switch 1A.

Owing to the presence of random noise in the super-regenerative circuit, the degree of build-up applied during each quenching cycle will, in general, be variable. In order to stabilize this effect, a part of the output from the rectifier V₄ is fed through a condenser C₃₀, to the control grid of a valve V₉, which includes in its anode circuit an iron-cored transformer L₁₀, L₁₁ tuned to the quenching frequency. The voltage across the winding L₁₀ is rectified by a diode V₈, and is applied from the load resistance R₂₂ to the grid of a valve V₇, where it appears in amplified form across the cathode resistance R₁₂. From here it is fed through a resistance R₁₇ and choke L₃ to the grid of the super-regenerative valve V₂, and, by reducing the gain of that valve, automatically checks any increase in the general level of the "noise" oscillations in the tuned circuit L₆, C₉.

Provision is also made to inhibit the responder circuits during the operation of any other radio transmitter that may be carried by the interrogated craft. For this purpose a suppressing voltage, synchronized with the other transmitter, is applied through a socket F₇ to a diode V₁₁, and through a resistance R₃₃ to the grid of a valve V₁₀. The resulting negative impulses are applied by the valve V₁₀ through a condenser C₃₁ and resistance R₂₈ to the grid of the valve V₂, and through a condenser C₃₃ and resistance R₂₉ to the grid of the quenching valve V₁, and throw both these valves out of action. Simultaneously a positive voltage is fed from the cathode resistance R₃₀ of the valve V₁₀ through a condenser C₃₄ to the cathode of the rectifier V₄ to render that valve non-conductive. As a result the responder is temporarily rendered insensitive to all signals, including those from the local transmitter.

The aerial tuning condenser C₉ is driven from a motor-generator through a cam-shaft which simultaneously controls the coding devices. One cam-operated contact, not shown periodically interrupts the high-tension supply to the valves V₂, V₃. Another cam, energises a relay, not shown, to close, the switch 1A which brings the condenser C₁₉ into parallel with the condenser C₂₀ for variable width coding. An extra wide pulse may be radiated as a distress signal and for this purpose a third cam energises another relay, not shown which (a) closes a switch 1 to 75 zero.

bring a condenser C₂₁ into parallel with the condenser C₂₀, and (b) closes a switch 4 to bring resistance R₁₃ into parallel with a resistance R₁₄. A switch 3 connects a condenser C₁₄ across the cathode resistance R₅ of the oscillator V₃ in order to condition that circuit to the wide pulse, whilst a switch 2 serves to override the previously mentioned cam-operated H. T. control switch for the valves V₂, V₃ so as to provide an uninterrupted H. T. supply to the latter. A selector switch allows the operator to control the coding as required.

The arrangements for effecting cyclic variation of the aerial tuning circuit, and for effecting signal coding form no part of the present invention and are not, therefore, described in detail, the present invention being concerned, as previously indicated, with the methods of effecting stabilisation of the super-regenerative circuit by utilising the "noise" output of the receiver.

Referring now to Figure 2 of the drawings, a super-regenerative receiver valve, V₂, has in its anode circuit a tuned circuit, L₃, C₇, coupled to the aerial, not shown, by a coil, L₄. Bias potential is applied to the cathode of the valve V₂, from a tapping in a potentiometer comprising resistances R₄ and R₆. The quench voltage is supplied by an oscillator valve, V₁, operating at a frequency of 300 kilo-cycles per second. The voltage from the anode of this valve is supplied through the attenuating network, R₃, C₂, to the grid of the valve V₂. The output from the tuned circuit L₃, C₇, is rectified by the diode, V₃, and is then passed to signal amplifying and output stages as required, connected to a terminal T.

The output from the rectifier V₃, is also fed through condenser, C₉, to the grid of an amplifying valve, V₄, which constitutes the first amplifier in the automatic gain stabilising circuit. The anode circuit of the valve, V₄, contains a tuned output circuit, L₅, C₁₆, L₆, C₁₇ tuned to the quench frequency. The resulting voltage across secondary winding L₆ which represents a narrow band of the "noise" spectrum centered about the quench frequency is rectified by a diode V₅, and after smoothing by a resistance/capacity combination R₁₂, C₁₄, is applied to the grid of the direct current amplifying valve, V₆. The voltage developed across the cathode load resistance R₁₃ is applied as a bias potential to the grid of the regenerative receiver valve V₂, through a resistance, R₅, and has the effect of stabilising the operation of this valve. If, for any reason, the gain of the receiver and thus the noise voltage, tends to increase, compensation is effected by the resultant increase in the direct current bias voltage across the resistance, R₁₃, which, as stated, is fed to the control grid of the valve, V₂, and tends to reduce the gain of that valve. This means that any tendency for the receiver "noise" level to change is strongly resisted and in fact, a state of equilibrium is reached.

Provided that the super-regenerative properties of either of the receiver circuits described are maintained, any variations in tuning, supply voltages, components or other disturbing factors can only cause a slight change in the receiver noise. The magnitude of this change is only a very small fraction of that which would occur in the absence of the automatic gain stabilising circuit, and depends upon the gain of that circuit. If this gain were infinite the change in "noise" amplitude and, therefore, in the receiver sensitivity due to any external influence would be theoretically

The effect of modulation upon any signal which is being received is slight, due to the fact that the modulation frequency is generally outside the pass band of the output circuit of the valve, V4. If the receiver is required to operate on a pulsed transmission, as is the case with the apparatus described in my co-pending U. S. patent application S. No. 692,085 filed August 21, 1946, the pulses will have little effect on the stabilising system until their repetition frequency exceeds 2 kcs. when the stabilising circuit described tends to bias off the receiver reducing its sensitivity. The sensitivity to which the circuit adjusts the receiver, and thus the working gain of the receiver, may be set to the desired value by controlling the magnitude of the direct current bias potential applied to the receiving valve, V2, in any known manner, for example, by adjustment of the resistance, R13. The system may, therefore, be adjusted to maintain the receiver at its most sensitive state, in spite of external disturbing variations.

Although one application of the invention has been described with reference to Figure 1 of the drawings in connection with apparatus for effecting identification by means of interrogating and responding equipment, it will be seen from the example described with reference to Figure 2, to be of quite general application to regenerative circuit arrangements.

I claim:

1. A super-regenerative radio receiver circuit comprising a space discharge tube including a cathode, at least one control grid and an anode, positive feed-back means including a tuned circuit coupled between said anode and a control grid for providing regeneration, signal input and output circuits coupled to said tuned circuit, a source of quenching oscillations, means for applying said quenching oscillations between the control grid and cathode of said tube, a selective amplifier circuit tuned to the frequency of said quenching oscillations, connecting means between said signal output circuit and the input circuit of said amplifier, a rectifying device connected to the output circuit of said amplifier for converting the amplified quench frequency signal output of said amplifier into a direct-current voltage and further connection means for applying said direct-current voltage between a control grid and the cathode of said space discharge tube to control the sensitivity thereof.

2. A super-regenerative radio receiver circuit comprising a space discharge tube including a cathode, at least one control grid and an anode, positive feed-back means including a tuned circuit coupled between said anode and a control grid for providing regeneration, signal input and output circuits coupled to said tuned circuit, a source of quenching oscillations, means for applying said quenching oscillations between the

control grid and cathode of said tube, a selective amplifier circuit tuned to the frequency of said quenching oscillations, connecting means between said signal output circuit and the input circuit of said amplifier, a rectifying device connected to the output circuit of said amplifier for converting the amplified quench frequency signal output of said amplifier with a direct-current voltage and a direct-current thermionic amplifier circuit including a space discharge tube having an output load resistance in its cathode circuit, connection means for feeding said direct-current voltage to the input circuit of said direct-current amplifier and further connecting means between said output load resistance and the cathode and a control grid of said first space discharge tube suitable for controlling the sensitivity of the tube by change of their relative potentials.

3. A super-regenerative radio receiver circuit comprising a space discharge tube including a cathode, a control grid and an anode, positive feed-back means including a tuned circuit coupled between said anode and a control grid for providing regeneration, signal input and output circuits coupled to said tuned circuit, a source of quenching oscillations, means for applying said quenching oscillations between the control grid and cathode of said tube, a selective amplifier circuit tuned to the frequency of said quenching oscillations, connecting means between said signal output circuit and the input circuit of said amplifier, a rectifying device connected to the output circuit of said amplifier for converting the amplified quench frequency signal output of said amplifier with a direct-current voltage and a direct-current thermionic amplifier circuit including a space discharge tube having an output load resistance in its cathode circuit, connection means for feeding said direct-current voltage to the input circuit of said direct-current amplifier and means connecting said output load resistance and the cathode and control-grid of said first space discharge tube for increasing the negative potential of said control-grid in response to an increase in amplitude of the quench frequency output of said selective amplifier circuit.
